UNITED STATES PATENT OFFICE.

WILLIAM MICHEAL MURPHY, OF NEW YORK, N. Y.

ELECTRIC BLOCK-SIGNALING SYSTEM.

SPECIFICATION forming part of Letters Patent No. 791,429, dated May 30, 1905.

Application filed August 31, 1904. Serial No. 222,833.

To all whom it may concern:

Be it known that I, WILLIAM MICHEAL MURPHY, a citizen of the United States of America, residing in the borough of Manhattan, city, 5 county, and State of New York, have invented certain new and useful Improvements in Electric Block-Signaling Systems, of which the following is a specification, reference being had therein to the accompanying drawings.

10 My invention relates to signal systems, and is especially adapted and designed for use on electric railways; and its particular object is the utilization of electric current used for the propulsion of trains to control the operation 15 of the danger signal or signals, the semaphore-circuits being controlled by means of differential relays.

The foregoing and other features of my invention will now be described in connection 20 with the accompanying drawings, forming a part of this specification, in which I have represented the system embodying my improvements in their preferred forms, after which I shall point out more particularly in the claims 25 those features which I believe to be new and of my own invention.

Figure 1 represents a diagrammatical sketch of two blocks of a standard railroad with their wiring-diagrams, showing in circuit the semaphores (one set at "danger" and the other 30 "clear") and the differential relays D D' for operating semaphores S S' by controlling their respective circuits. Fig. 2 represents a modification of my system illustrated by 35 Fig. 1.

Like letters and numbers represent the same parts in both blocks, using the prime numbers for the danger-block.

The tracks are represented by a continuous 40 rail R, which is connected direct to the source of power P, and by a rail made up of insulated block-sections B and B', &c., insulated from each other at I and I', &c., respectively. The resistances 16 and 16' are shown electrically 45 connected between the continuous rail R and the blocks B and B', respectively, and are so connected to offset the equal ratios of the coils in relays D and D'. The resistance 16 in the differential-relay circuit controls the operation 50 of the semaphore-circuit by magnetizing

the core D, because coil 10 predominates. When short-circuited, the coils 9 and 10 neutralize each other, and thereby demagnetize the core D, allowing the semaphore to go to "danger" by gravity. The semaphores S and 55 S', &c., are any well-known type controlled by solenoid-magnets or any other preferred type. The differential relays D and D' consist of two or more coils of equal ratio wound in opposite directions upon a single core having at one end a swinging armature 3 and at the other swinging armature 4, held by springs 5 and 6, respectively. Coils 10 and 9 are normally energized, the former by current flowing direct to the rail R, the latter by current flowing through resistance 16. Coil 10 therefore predominates and magnetizes the core D 60 strongly enough to hold down armature 4, but not armature 3. The action of either coil alone upon core D energizes it sufficiently 65 to cause it to attract 3, thereby breaking the semaphore-circuit at 13, allowing it to go to "danger." Armature 3 is to serve only as a precautionary measure in the event of an 70 emergency; (such as open connection in circuits 9 or 10,) whereby energizing the core D overcomes the tension of spring 5, which 75 opens the semaphore-circuit 13, allowing the signal to go to "danger."

Following out the circuits, C is connected to 80 source of power and is opposite to R, branching out at 8 through magnets 9 and 10, wound upon the core forming the differential relay D. The other side of magnet 9 is electrically connected to block B and resistance 16 85 and terminating at continuous rail R, while the other end of magnet 10 is electrically connected direct to the continuous rail R, the semaphore-circuit beginning at C, 11, through armature 4, connection 12, armature 3, connection 13 to semaphore-solenoid 14, thence by connection 15 to rail R, thereby energizing solenoid 14 and holding the signal at "safety." 90

The *modus operandi* of the system is as follows: The normal condition of the system will 95 show the road "clear." When a train enters a block, the resistance 16 is short-circuited. Rail B is connected direct to rail R through the wheels and axles, thereby allowing current in coil 9 to become of equal strength with 100

that in coil 10. Coils 9 and 10 therefore neutralize each other. Spring 6 retracts armature 4, thereby breaking the circuit through solenoid 14, which normally holds the semaphore at "safety," and thus allows the semaphore to go to "danger" by gravity.

A modification of my system (illustrated by Fig. 2) would be one in which the same differential relay is used, but only supplied with one armature, and individual magnets 9 and 10 are electrically connected in each one of the two circuits to accomplish the precautionary measure provided by my armature 3 of magnet D. In this modification the three armatures of each of the three separate magnets are connected in series with the semaphore-circuit.

I do not propose to limit the claims of the semaphore-circuits, as I do not claim any particular system whatever, whether it be single or overlapping system or any other system known to the art; but I do want to specifically limit myself to the controlling of each signal of each block by a differential relay or magnets fully described in the foregoing specification for controlling of any semaphore-circuits which I may hereafter adopt.

The resistances 16 and 16', &c., are shown diagrammatically between R and B and R and B', &c., respectively; but I do not want to limit myself to this detail of connection, because the resistance may be connected in either circuit of the differential relay at any other point.

35 I show in the illustration that I mean to use the same source of power that is used for propulsion of cars; but I may employ local or primary batteries, if desired.

Having described my invention, what I claim herein as new, and what I desire to secure by Letters Patent, is—

40 1. In an electric block-signaling system where a differential relay controls the semaphore-circuit, means for utilizing the same source of power as for the propulsion of trains to control the operation of the signals.

45 2. In an electric block-signal the combination of a block-section consisting of a continuous rail and a rail divided into sections, the sections being insulated from each other and connected by resistance to the continuous rail, a source of power, a differential relay, the coils of which are normally energized; through one coil, the current flows direct to the continuous

rail, while through the electrically-opposed 55 coil the current flows through resistance to the continuous rail, substantially as set forth.

3. In an electric block-signal system the combination of a block-section consisting of a continuous rail and a rail divided into sections, 60 the sections being insulated from each other and connected by resistance to the continuous rail, a source of power, a differential relay the coils of which are normally energized; through one coil current flows direct to the continuous 65 rail, while through the electrically-opposed coil the current flows through resistance to the continuous rail, actuating means for controlling the semaphore-circuit by neutralizing the action of the coils of the differential relay by 70 the presence of the car on that block, allowing the signal to go to danger by gravity.

4. In an electric block-signal system the combination of a block-section consisting of a continuous rail and a rail divided into sections, 75 the sections being insulated from each other and connected by resistance to the continuous rail, a source of power, a differential relay, the coils of which are normally energized; through one coil current flows direct to the continuous 80 rail, while through the electrically-opposed coil the current flows through resistance to the continuous rail, actuating means for controlling the semaphore-circuit by neutralizing the action of the coils of the differential magnet 85 by short-circuiting the resistance between the rails, allowing the signal to go to danger by gravity.

5. In an electric block system the combination of a block-section, consisting of a continuous rail and a rail divided into sections, the sections being insulated from each other and connected by resistance to the continuous rail, a source of power, a differential relay, the coils of which are normally energized, through one 90 95 coil current flows direct to the continuous rail, while through the electrically-opposed coil the current flows through resistance to the continuous rail, actuating means for controlling the semaphore-circuit when an open connection appears in the circuit of either coil of the differential relay.

This specification signed and witnessed this 24th day of August, A. D. 1904.

WILLIAM MICHEAL MURPHY.
